ALARM DISPATCHING MECHANISM

Joseph F. Ebert, Hollis, N. Y., and Tellef A. Terjesen, Hoboken, N. J., assignors to Signal Engineering & Manufacturing Company, New York, N. Y., a corporation of Massachusetts

Original application August 23, 1934, Serial No. 741,140, now Patent No. 2,077,099, dated April 13, 1937. Divided and this application May 12, 1936, Serial No. 79,332

1 Claim. (Cl. 287—52.03)

The present application is a division of our original application, Serial No. 741,140, filed August 23, 1934, now Patent No. 2,077,099 of April 13, 1937 for a Fire alarm dispatching mechanism, and relates particularly to a dispatching mechanism, by the operation of which a given code is sent, in accordance with the arrangement of code determining projections on a rotatable element, usually known as a code wheel.

According to the invention of the present application, there is provided an improved mounting for code determining elements, which permits an element to be readily removed and another element substituted therefor, in order to change the code designation of a particular sending station, without in any way disturbing any other part of the dispatching mechanism. The improved construction also insures that the substituted code determining element will occupy the same angular position on its operating shaft as did the element which has been removed. The above and other advantageous features of the invention will hereinafter more fully appear from the following description taken in connection with the accompanying drawing, in which:

Fig. 1 is a view in side elevation, of a dispatching mechanism embodying the invention.

Fig. 2 is a view in end elevation of the parts shown in Fig. 1, as viewed from the left.

Fig. 3 is a fragmentary view, illustrating the mounting of the code determining element.

Fig. 4 shows the element of Fig. 3 removed from its operating shaft.

Like reference characters refer to like parts in the different figures.

Referring first to Figs. 1 and 2, the dispatching mechanism, shown as having been removed from the alarm box or station in which it is normally mounted, is adapted to be actuated by a hand lever 1 accessible from the outside of the box. The lever 1 is mounted on a shaft 2, and turning of the lever in the direction of the arrow in Fig. 1 causes a toothed sector 3 on the shaft 2 to turn a pinion 4 mounted on a shaft 5. The shaft 5 also is connected to a spring 6, shown in dotted lines, within a casing 6a carried by the frame plate 7, and this spring is wound by turning of the lever 1. Consequently, upon release of the lever 1 at the end of its operating movement, the tension of the wound spring 6 on the shaft 5 actuates the dispatching mechanism. The shaft 5 also carries a gear 8 in mesh with a pinion 9 on a shaft 10 on which is also mounted a code determining element or wheel 11, the construction of

which constitutes the subject matter of the present invention.

The code wheel 11 provides around its periphery a number of code determining projections 11a, and rotation of the wheel 11 causes these projections 11a to operate a pivotally mounted arm 12. The arm 12 provides a projection 13, of insulating material, which is disposed between a pair of contact members 14 and 15. Normally, contact tips 14a and 15a on these contact members 14 and 15 are in engagement as shown, but when a code projection 11a engages the arm 12, turning of the latter in a clockwise direction about its pivot 12a causes the arm projection 13 to disengage the contact tip 14a from the contact tip 15a. As the projections 11a on the code wheel 11 successively engage the arm 12, an oscillatory movement is imparted to the arm 12 which results in successive disengagement and reengagement of the contact members 14 and 15. This operation of the contacts causes signal impulses to be transmitted through the signal system, in which the mechanism is connected, which system forms no part of the present invention.

As previously pointed out, the present invention contemplates an improved mounting of the code wheel 11, whereby the latter may readily be removed from the shaft 10, and this mounting is best shown in Figs. 3 and 4. To this end, the wheel 11 carries a bracket 16 having an opening 17 extending therethrough for freely receiving the projecting end of the shaft 10. The bracket 16 also provides a slot 18 for receiving a pin 19 extending transversely through the shaft 10. Therefore, when the shaft 10 is passed through the opening 17 in the bracket 16 with the pin 19 received in the slot 18, the code wheel 11 is adapted to rotate with the shaft 10. After a code wheel 11 has been so positioned on the shaft, it is secured against removal therefrom by turning set screws 20 to draw together portions of the bracket on opposite sides of the slot 18, thereby causing the bracket to hold the pin 19 tightly. These screws 20 are readily accessible from the left-hand side of the device, as viewed in Fig. 1, in which the screws are shown in dotted lines.

When it is desired to remove the code wheel 11 and replace it with another wheel having a different code determination, it is only necessary to loosen the screws 20 and withdraw the wheel from the shaft 10. Then when a wheel 11 having a different code determination is placed on the shaft with the screws 20 facing, as shown in Figs. 1 and 2, the pin 19 engaging with the slot 18 of the new wheel insures that the new wheel will

occupy exactly the same angular position on the shaft 18 as did the wheel just removed. This insures that when code wheels are changed on the dispatching mechanism, there is no possibility of the code being mis-sent by the new wheel, owing to it being positioned on the shaft 10 in the wrong angular relation with respect to the contact operating arm 12.

From the foregoing, it is apparent that by the present invention there is provided an improved alarm dispatching mechanism characterized by the fact that the code determining element of the mechanism can be quickly removed and a different element substituted therefor, without any possibility of such substitution causing any disturbance in the timing of the mechanism, when operated.

We claim:

In an alarm dispatching mechanism, a rotatably driven code wheel shaft providing a pin extending transversely to the axis of the shaft, a code wheel providing a mounting having an opening for freely receiving the end of the shaft, beyond said pin, a slot provided in said mounting on opposite sides of said opening for receiving said pin, and means accessible from one side only of said wheel for compressing the walls of said slot on said pin to clamp the code wheel on said shaft.

JOSEPH F. EBERT.
